MAGNETICALLY SHIELDED CUTOUT FOR
ELECTRIC MOTORSThomas S. Taylor, Caldwell, N. J., assignor to
The Singer Manufacturing Company, Eliza-
beth, N. J., a corporation of New Jersey

Application December 11, 1937, Serial No. 179,235

4 Claims. (Cl. 172—279)

This invention relates to electric motors, more particularly of the single-phase induction type having a main exciting winding and a starting winding with a speed-responsive switch or cutout to open the circuit through the starting winding when the motor comes up to speed.

Speed-responsive cutouts for motors of the type in question commonly employ a weighted member which is biased by one or more springs in a direction opposite to the direction in which it tends to move under centrifugal force. For reliable operation, the cutout biasing spring or springs must be calibrated and must be made of a material which will retain a constant resiliency over long periods of use. Steel springs are found to be suitable for the purpose but are often found to be affected by stray magnetic fields in the motor causing them to vibrate noisily.

The present invention therefore has for an object to provide an induction motor with a speed-responsive cutout which is free from vibrating spring noise.

With the above and other objects in view, as will hereinafter appear, the invention comprises the devices, combinations, and arrangements of parts hereinafter set forth and illustrated in the accompanying drawing of a preferred embodiment of the invention, from which the several features of the invention and the advantages attained thereby will be readily understood by those skilled in the art.

In the accompanying drawing, Fig. 1 is an axial section of an induction motor embodying the invention. Fig. 2 is a similar section through the rotor of the motor taken in a plane 90° from the plane of the section shown in Fig. 1. Fig. 3 is a section on the line 3—3, Fig. 1. Fig. 4 is an internal face view of the cutout switch device. Fig. 5 is a top edge view of the switch device. Fig. 6 is a section on the line 6—6, Fig. 4. Fig. 7 is a section on the line 7—7, Fig. 4, and Fig. 8 is a diagrammatic representation of the motor.

The motor has a frame including the laminated stator core 1 to which is clamped end-bonnets, one of which is shown at 2, having bearings 3 for the shaft 4 of the rotor body 5 supporting the integrally cast aluminum bars 6 and end-rings 7 of the conventional squirrel-cage secondary winding. The stator 1 carries the conventional main and starting windings M and S of the conventional split-phase motor indicated in Fig. 8.

The cutout C for the starting winding preferably comprises a molded base 8 of insulating

material having holes 9 in which are riveted the pivot hooks 10 for the sheet-metal levers 11 and 12. The lever 11 is the actuating lever whereas the lever 12 is the actuated lever and carries the movable contact 13 which at times, engages the stationary contact 14 on the terminal plate 15. A toggle thrust-member comprising a bar 16 and compression coil-spring 17 are interposed between the levers 11 and 12. The toggle thrust-member insures a snap action or quick make and break of the switch contacts and works on the same principle as that disclosed in the U. S. patent of J. M. Naul, No. 2,083,343, dated June 8, 1937.

A recovery spring 18 is interposed between the base 8 and lever 11 to bias the latter in a direction to open the switch contacts 13, 14. The tail 19 of the lever 11 engages a stop-surface 20 on the base 8 to limit the motion of the lever 11 under the influence of the spring 18. The lever 11 carries two felt pads 21 for rubbing engagement by the collar 22 of molded insulating material which is slidable on and endwise of the shaft 4.

The collar 22 is engaged by the inturned arms 23 of the weighted levers 24, 24 together and yieldingly draw them toward the shaft 4, thereby causing the arms 23, 23 to force the collar 22 against the felt pads 21 and shift the switch lever 11 in a direction to close the switch contacts 13, 14; the springs 28 being strong enough to overcome the resistance of the spring 18. The springs 28 closely overlie the end-rings 7, as shown in Figs. 2 and 3.

A pair of calibrated steel coil-springs 28, 28 connect the weighted levers 24, 24 together and yieldingly draw them toward the shaft 4, thereby causing the arms 23, 23 to force the collar 22 against the felt pads 21 and shift the switch lever 11 in a direction to close the switch contacts 13, 14; the springs 28 being strong enough to overcome the resistance of the spring 18. The springs 28 closely overlie the end-rings 7, as shown in Figs. 2 and 3.

It has been found that the construction above described is noisy in operation and careful investigation and study have revealed that the noise is caused by lateral vibration of the springs 28 in the stray magnetic field adjacent the rotor end-rings 7. This noise has been eliminated by interposing between the end-ring 7 and springs 28 a thin sheet-metal plate 29 of magnetic metal such as sheet-iron having ends 30 bent at right angles to the plane of the plate 29 so as to partially surround the springs 28. The plate 29 may be spot-welded at 31 to the frame 27. This plate 29 with its angularly bent ends 30 constitutes a magnetic shield for the springs 28 and eliminates noisy vibration of the latter. Steel

springs may thus be used instead of non-magnetic springs such as phosphor-bronze springs which are found not to maintain a constant calibration over a length of time required for practical service. Each of the springs 28 lies in a trough of magnetic metal embracing three sides of the spring and constituting an effective magnetic shield for such spring.

This invention is not to be understood as limited to the details of construction and relative arrangement of parts shown and described, as the foregoing disclosure is made in an illustrative sense and not in limitation of the invention, the scope of which is indicated by the appended 15 claims.

Having thus set forth the nature of the invention, what I claim herein is:

1. In an alternating current motor, a stator having an exciting winding, a rotor body disposed 20 within the field of said stator, a rotor shaft, a speed-responsive device mounted on the rotor shaft and including a coil spring-biased weighted member, a sheet-iron magnetic shield interposed between said rotor body and said spring, and 25 motor starting means governed by said speed-responsive device, said shield having an end-portion bent to stand in a plane at an angle to the plane of the shield proper and paralleling the axis of said spring.
2. In an alternating current motor, a stator having an exciting winding, a rotor body disposed 30 within the field of said stator, a rotor shaft, a speed-responsive device mounted on the rotor shaft and including a pair of weighted levers, a 35 pair of coiled steel tension-springs connecting

said levers, a sheet-iron magnetic shield presenting spaced troughs each containing a respective one of said springs and disposed between said springs and the rotor body, and a cutout switch under the control of said speed-responsive device. 5

3. In an alternating current motor, a stator having an exciting winding, a squirrel cage rotor body disposed within the field of said stator and including conductor bars and connecting end rings, a rotor shaft, a speed-responsive device 10 mounted on the rotor shaft and including a coil-spring-biased weighted member, a trough-shaped shield of magnetic metal containing said coil-spring and disposed between the latter and the adjacent end ring of said rotor body, and motor 15 starting means governed by said speed-responsive device.

4. In an alternating current motor, a stator having an exciting winding, a squirrel cage rotor body disposed within the field of said stator, said 20 body having conductor bars and connecting end rings, a rotor shaft, a speed-responsive device mounted on the rotor shaft and including a frame, a weighted lever pivoted on said frame, a steel spring to bias said lever in a direction toward the rotor shaft, said spring being disposed closely adjacent one of the end rings of said rotor body and extending in a direction parallel to the adjacent face of the adjacent end ring, and a 25 sheet of magnetic metal disposed between said spring and said adjacent end ring and having an edge portion bent to stand at an angle to the plane of said sheet proper and paralleling said spring. 30
